UNITED STATES PATENT OFFICE

SAMUEL I. BERGER, OF NEWARK, NEW JERSEY

TRAFFIC-SIMULATING TOY

Application filed July 14, 1928. Serial No. 292,662.

My present invention is concerned with power driven or hand operated mechanical toys which may assume many forms but finds its preferred embodiment in a traffic simulating toy of the general character disclosed in the patent to Louis Marx, No. 1,674,293, granted June 19, 1928.

An object of the invention is to provide an improved toy, particularly in respect to ruggedness, durability, simplicity of construction and economy of manufacture.

Another object is to provide a sheet metal toy embodying numerous small moving parts as well as stationary parts which are so designed that the danger of a child cutting or scratching its hands or otherwise injuring itself while operating the toy, or carrying it about, is reduced to a minimum.

Another object is to provide a toy of this character in which not only the movement but the rattle and clatter of traffic is effectively simulated.

Another object is to provide a toy in which the driving means, while highly effective under the rough usage and careless handling to which the toy may be subjected is sufficiently non-positive to prevent permanent injury thereto in case the moving parts jam and a child attempts to inexpertly force the parts into motion.

With the above noted and other objects in view, the invention consists in certain novel features of construction and combinations and arrangements of parts which will be more fully hereinafter described and pointed out in the claims.

The invention may be more fully understood from the following description in connection with the accompanying drawings, wherein:

Fig. 1 is a perspective view of a toy embodying the invention.

Fig. 2 is an enlarged broken bottom plan view thereof.

Fig. 3 is a transverse sectional view on the line 3—3 of Fig. 2.

Fig. 4 is a longitudinal sectional detail on the line 4—4 of Fig. 3.

Fig. 5 is a transverse sectional view on the line 5—5 of Fig. 2.

Fig. 6 is an enlarged sectional detail on the line 6—6 of Fig. 2, and

Fig. 7 is a similarly enlarged detail view on the line 7—7 of Fig. 5.

The toy includes a platform portion provided with an endless, approximately oval or loop-shaped slot 10 which divides the platform into an inner section 11 and surrounding outer section 12.

Vehicle simulating toys 13, travelling on the platform are connected through the slot 10 to an endless driving cable 14 beneath the platform. The toys 13, moving in opposite directions along the parallel elongated runs of the endless slot, simulate oppositely moving traffic streams and the passage of the vehicle toys around the arcuate end runs of the slot is substantially concealed by housings 15 and 16 secured to opposite ends of the platform.

The cable 14 travels around a pair of pulleys 17, 18 mounted under opposite ends of the platform, one of said pulleys being driven by a conventional spring motor (not shown) concealed in an upward extension 15^a of housing 15 and provided with the usual winding key 19 and stop-and-start lever 20.

Fixed upon the inner (and if desired the outer) platform sections are a plurality of toy figures such as 20, 21, 22, 23 and 24. The figures may represent various characteristic and familiar street figures and fixtures such, for instance, as pedestrian traffic and stationary street ornaments. In the present case they simulate respectively a push cart vender, a street clock, a traffic officer, a pedestrian and an equestrian statue. Certain of the figures, such for instance, as the dominating figure of the traffic officer, may be deliberately made out of proportion to the others, thereby enhancing the grotesque and amusing appearance of the toy.

Means is provided for connecting the inner and outer platform sections together, such means preferably so joining the sections that they are sustained against relative movement in any direction. One convenient means for effecting this connection includes the traffic tower or street-lighting fixture-simulating means illustrated. The lighting fixtures

include posts or standards 26, 27 and 28, the central standard being fixed to the central platform section 11, the end standards 26 and 28 being fixed to the outer platform section 12. All three standards are integrally connected at their tops by bridging pieces 29, which bridging pieces cooperate with the standards to define arch structures spanning the parallel runs of the loop slot and under which the two lines of traffic run.

The housings 15 and 16 also serve to connect the inner and outer platform sections. These housings straddle the platform and the lower edges of the sides of the housings extend between a downwardly turned flange 30 at each side of the platform and an upwardly rolled bead 31 integral with the flange. As best seen in Fig. 6, the lower edges of the housings are provided with bendable tongues 32 turned inwardly through slots 33 in the flange 30, whereby the sharp lower edges of the housing members are concealed and protected by bead 31. In this manner, the danger of a child injuring its hands on the sharp corners of the housing members is considerably lessened. The front or adjacent walls of the housings define openings 34 aligned with the two longitudinal runs of the slot 10 and the moving toy vehicles pass into and out of the housings through these openings. Between the openings 34, a downward column-simulating extension 35 of the front wall of the housing is connected to the central platform section 11.

Supplementing the housings and the toy lighting fixtures to connect the two sections of the platform, are bracing members, consisting of transversely disposed, upwardly facing channel bars 36 arranged under the platform. The edges of these channel bars are formed with bendable tongues 37 passed upwardly through slots 38 in the platform and bent over upon the top of the platform. Such slot and tongue connections serve to unite each channel member with both sections of the platform. The channel members are notched or cut away at 39 to provide clearance for the vehicle actuating cable 14. The connective channel pieces 36 are in themselves of general utility and embody structural features which permit the production of a strong bracing member from thin gauge sheet metal stock. Strength and rigidity is lent to the members 36 by the provision of an upwardly bowed longitudinal corrugation 40 struck from the intermediate portion of the channel and by the use of spaced indentations at 41 along the bending lines of the channels, which serve to provide strengthening webs, resistant both to transverse and longitudinal bending strains.

The means which is used for attaching the toy vehicles to their actuating cable is substantially similar to that illustrated in the prior patent above referred to. It consists

of a thin bar 42 freely vertically movable through the vehicle toys 13. Bar 42 is turned over as at 43 at its upper end, so that the toys cannot be lifted upwardly to disconnect them from the bar and at its lower end the bar is turned over and crimped as at 44 to the actuating cable 14.

Another feature of the invention is the novel manner in which one of the pulleys, preferably the idler pulley 18, is used to maintain a tension on the cable. As best seen in Figs. 3 to 5 inclusive, pulley 18 is mounted on a vertical axle 45, which axle passes upwardly through a longitudinal slot 46 in the platform and has a bearing in a hollow sheet metal carrier block 47 slidable longitudinally on the platform. Block 47 at its forward edge is provided with a downwardly turned guiding tongue 48 traveling in a slot 49 in the platform and at its rear edge is formed with a rearwardly extending tongue 50 passed through the column 35 and terminating in an upwardly turned finger 51. This finger is connected to the lower end of a flat spring 52, the upper end 53 of which is anchored in a slot 54 near the top of the housing 16.

Spring 52 normally tends to urge the block 47 rearwardly toward the column 35 and to hold the cable 14 taut. When, due to an inadvertent jamming of the traveling vehicle toys, or to any other casual cause, a strain is imparted to the cable, the yielding mounting of the pulley 18 serves to compensate for the strain and prevent the cable from being snapped. This compensating and tensioning mechanism not only serves to promote uniform movement of the traveling toys, but also minimizes the danger of snapping the cable or otherwise injuring the toy in the event that a child attempts to force the movement of a jammed vehicle-simulating element.

As in the prior patent, the platform edges adjacent slot 10 may be raised at 60 to simulate car tracks and it will be obvious that numerous other expedients might be resorted to for increasing the realistic appearance of the toy.

In operation, when the driving motor is wound and released, the cable carries all of the vehicle-simulating toys in an orbital path. In appearance, however, due to the fact that the vehicle movement at the ends of the slot is concealed, the toy appears to reproduce a street scene with continuously and oppositely moving traffic streams.

This realism is further accentuated by the noise produced by the whirring motor, the scraping (or if desired, rolling) of the vehicle toys along the platform and the clicking of the bar extensions 44 against the pulleys.

In order to avoid an unnecessary showing of conventional features, various connections, such, for instance, as the connections of the stationary figures and columns 35 to the plat-

form, are not illustrated. It will be understood, however, that these parts are joined together by ordinary slot and tongue connections such as those shown at 37, 38 or in any other conventional manner.

It will thus be seen that there is herein described a device in which the several features of this invention are embodied, and which device in its action attains the various objects of the invention and is well suited to meet the requirements of practical use.

As many changes could be made in the above construction, and many apparently widely different embodiments of this invention could be made without departing from the scope thereof, it is intended that all matter contained in the above description or shown in the accompanying drawings shall be interpreted as illustrative and not in a limiting sense.

Having thus described my invention, what I claim as new and desire to secure by Letters Patent is as follows:

1. A toy of the class described, including a platform having a slot therein, movable members on the platform, an endless cable beneath the platform, a pair of pulleys around which the cable runs, means connecting the movable members to the cable through said slot, means for driving one pulley, and yielding means mounting the other pulley.

2. A toy of the class described, including a platform having a slot therein, movable members on the platform, an endless cable beneath the platform, a pair of pulleys around which the cable runs, means connecting the movable members to the cable through said slot, means for driving one pulley, and yielding means mounting the other pulley, said means comprising a pulley-supporting member slidably mounted on the platform and a spring urging said member in a direction to hold the cable taut.

3. A toy of the class described, including a platform having a slot therein, movable members on the platform, an endless cable beneath the platform, a pair of pulleys around which the cable runs, means connecting the movable members to the cable through said slot, means for driving one pulley, and yielding means mounting the other pulley, said means comprising a pulley-supporting member slidably mounted on the platform and a spring urging said member in a direction to hold the cable taut, said pulley-supporting means comprising a hollow block and a slot and tongue connection between the platform and the block to guide the sliding movement of the latter.

4. A toy of the class described, including a platform having a slot therein, movable members in the platform, an endless cable beneath the platform, a pair of pulleys around which the cable runs, means connecting the movable members to the cable through said slot, means

for driving one pulley, yielding means mounting the other pulley, an upright on the platform, and a spring anchored thereto, the yielding pulley-mounting means including a pulley carrier slidably mounted on the platform and connected to the spring.

5. A toy of the class described, including a platform having a slot therein, movable members on the platform, an endless cable beneath the platform, a pair of pulleys around which the cable runs, means connecting the movable members to the cable through said slot, means for driving one pulley, yielding means mounting the other pulley, a housing on the platform through which the movable members travel, and a spring concealed within the housing, the yielding pulley mounting including a slidable pulley carrier connected to the spring.

6. A toy of the class described, including a platform having a slot therein, movable members on the platform, an endless cable beneath the platform, a pair of pulleys around which the cable runs, means connecting the movable members to the cable through said slot, means for driving one pulley, yielding means mounting the other pulley, a housing on the platform through which the movable members travel, a spring concealed within the housing, the yielding pulley mounting including a slidable pulley carrier connected to the spring, said carrier comprising a hollow block slidable on the platform and having a guiding connection therewith.

7. A toy of the class described, including a platform having a slot therein, movable members on the platform, an endless cable beneath the platform, a pair of pulleys around which the cable runs, means connecting the movable members to the cable through said slot, means for driving one pulley, yielding means mounting the other pulley, a housing on the platform through which the movable members travel, a spring concealed within the housing, the yielding pulley mounting including a slidable pulley carrier connected to the spring, said carrier comprising a hollow block slidable on the platform and having a guiding connection therewith, the spring being flat, connected at its upper end to an upright section of the housing and at its lower end to an extension of the block.

8. A toy as set forth in claim 7 and wherein the block extension comprises a tailpiece slidably through one wall of the housing and provided with an upturned finger to which the spring is attached.

9. In a toy of the class described, a platform member and a housing mounted thereon, the platform member including depending marginal flanges to space the platform above a supporting surface, said flanges at their lower edges being rolled upwardly to form beads, the sides of the housing member entering between said beads and flanges.

10. In a toy of the class described, a platform member and a housing mounted thereon, said platform member including depending marginal flanges to space the platform
5 above a supporting surface, said flanges at their lower edges being rolled upwardly to form beads, the sides of the housing member entering between said beads and flanges, and having concealed slot and tongue connections
10 with the flanges.

11. In a toy of the class described, a platform including a pair of sections, lying in the same plane and separated from each other by an endless slot, light gauge sheet metal
15 bracing bars under the platform connecting the sections, said bars being of upwardly facing channel formation having slot and tongue connections with both panel sections and being indented at spaced points along their
20 longitudinal bending lines to provide strengthening webs.

12. As a new element in a fabricated sheet metal toy, a connective bracing bar of thin gauge sheet metal stock, said bar being of
25 channelled formation, longitudinally corrugated along its intermediate portion and having spaced, web-forming indentations along its bending lines.

Signed at Newark in the county of Essex
30 and State of New Jersey, this 12th day of July, A. D. 1928.
